HAIR CURLING DEVICE

Max Haberman, Forest Hills, N. Y.

Application April 14, 1942, Serial No. 438,868

9 Claims. (Cl. 132—33)

This invention relates to improvements in hair curling devices for the curling of human hair.

One of the important features of the invention resides in a hair waving device by the use of which, an individual may without an attendant, prepare the hair and produce curls comparable to those produced by a professional hair dresser.

Another feature of the invention is to provide a hair curling device by which a tress of hair may be tightly wound and securely held to produce a relatively tight curl.

A further feature of the invention is the provision of a hair waving device in which the curler member on which the tress of hair is wound is of substantially cage-like construction to enable circulation of air therethrough to facilitate quick drying of the hair when water or lotions are used, and which is inducive of ventilation for the comfort of a user.

A still further feature of the invention is to provide a hair curler which is secured against accidental displacement by a clip of "bobby pin" style which grips the outer convolution of hair when the tress is fully wound upon the curler.

A still further feature of the invention resides in a hair curling device embodying a curler member and a separable manipulating key member, the key member facilitating the easy and convenient turning of the curler member during the hair winding operation, whereas the key member may be disconnected from the curler member when the tress is fully wound upon the curler member to relieve the weight of the same upon the head of a user and to avoid bulkiness during the period of time that the curler member must remain upon the head of a wearer to produce the desired curl.

Other features of the invention will appear as the following specification is read in conjunction with the accompanying drawing, in which

Figure 1 is a side elevational view of the hair curler device ready for use with the pivoted clamp shown in open position in dotted lines.

Figure 2 is a top plan view.

Figure 3 is an enlarged vertical longitudinal sectional view on the line 3—3 of Figure 2.

Figure 4 is an enlarged vertical transverse sectional view on the line 4—4 of Figure 1, but showing a tress of hair fully wound upon the curler member.

Figure 5 is a perspective view of the curler member per se.

Figure 6 is a side elevational view of a modified form of the invention, illustrating the pivotal

clamping bar in inoperative position in full lines and in operative position in dotted lines.

Figure 7 is an enlarged vertical transverse sectional view on the line 7—7 of Figure 6.

Referring to the drawing by reference characters, the numeral 10 designates the hair curler device in its entirety and which includes a curler member A, and a separable winding key member B.

The curler member A comprises a cylindrical and tubular cage-like body 11, preferably made from metal although the same may be constructed of other materials such as rubber if desired. By constructing the body 11 of substantially cage-like shape, the same is provided with elongated slots 12 for ventilating purposes as will be hereinafter appreciated. One of the ends of the body 11 is open, while the other end is provided with an annular inwardly extending flange 13 which freely extends into the annular groove 14 provided in an end closure or head 15. By this construction, the head 15 is swivelly connected to one end of the body 11 so that either the head or body may be turned relative to each other.

Fixed to the head 15 is one end of a resilient clip 16, the said end being provided with a loop portion 17 and terminating in an attaching flange 18 which fits into a slot 19 in the head 15 and which flange is secured by a rivet 20 extending transversely through the head and through openings in the flange 18. The loop portion 17 permits of the outward flexing of the clip 16 as the convolutions of hair are wound upon the cylindrical body 11 during a hair curling operation.

The clip 16 is of the "bobby pin" type, and its free end is bent outwardly and extends slightly beyond the open end of the body 11. Normally the clip 16 is disposed against the exterior of the body 11 as best illustrated in Figures 1 and 3 of the drawing.

The winding key member B comprises a body portion 21 of a diameter to snugly and slidably fit within the tubular body 11 and integral with the body portion 21 and disposed axially with respect thereto is a handle portion 22, the end of which is knurled as at 23 to facilitate tight gripping by the fingers of the hand of an operator during a hair winding operation. The winding key member B is employed for imparting a winding or turning movement to the tubular body 11 and relative to the head 15 and clip 16, and it is preferable to provide releasable interengaging means between the body portion 21 of the winding key and the cage-like body 11. This interlocking means consists of a catch member

24 disposed within a slot 25 in the body portion 21, the said catch being pivoted adjacent the handle portion 22 as at 26. The free end of the catch member 24 is provided with an outwardly extending tooth 27 which is engageable in any one of a plurality of keeper openings 28 provided in the walls of the tubular body 11. The keeper openings 28 are arranged in the same circumferential plane and at relatively close spaced distances so that after the body portion 21 of the winding key is inserted into the cage-like body 11, the tooth 27 will snap into one of the keeper openings 28 by a slight turning of the key member relative to the curler member. A leaf spring 29 has one of its ends fixed to the body portion 21 and its other end extending into the slot 25 to press against the catch 24 in order to urge the toothed end of the catch member outwardly. The catch member 24 is provided with an outwardly extending finger piece 30 adjacent the handle portion 22 to facilitate depressing of the catch member 24 in order to release the tooth 27 from its engaging recess.

For gripping the free end of a tress of hair against the winding member A preparatory to curling of the same by the manipulation of the handle portion 22 of the key member, I provide a clamp 31 having inwardly turned or bent ears 32 which embrace opposite sides of the handle portion 22 and said ears are pivoted to the handle portion by the pivot pin 26 hereinbefore described. The clamp 31 includes a flat elongated jaw portion 32 which normally lies against and extends parallel to the body portion 11 of the curler member A. A spring 33 is coiled about the pivot 26 and has one of its ends bearing against the handle portion 22 and its other end extending against the under side of a finger or tail piece 34. This spring tends to urge the jaw portion 32 into clamping engagement with the cage-like body 11. In view of the fact that the clamp 31 overlies the finger piece 30 of the catch 24, the clamp member is provided with an elongated slot 35 through which the finger piece 30 extends.

In practice, the curler member A, and the winding key member B are connected together in the manner shown in Figures 1 and 2, wherein the tooth 27 of the catch 24 is in one of the keeper openings 28, thus the two parts are locked together so that turning of the winding key member B will impart a corresponding winding movement to the curler member A. The first step for producing a curl by the use of this device is to depress the finger piece 34 as shown in dotted lines in Figure 1 in order to open the clamping jaw 31. The tress of hair is prepared and the free end of the hair is placed beneath the open jaws 31 and the operator releases the pressure upon the finger piece 34 whereby the spring 33 holds the jaw portion 31 against the free end of the tress of hair. With one hand gripping the knurled portion 23 of the key member B while the other hand grasps the head 15, the operator proceeds to turn the key member B to wind the tress of hair about the cage-like body 11 of the curler member A. As the convolutions of the hair build up, the clip 16 moves outwardly due to the resiliency of the loop portion 17. When the entire length of the tress of hair has been wound upon the cage-like body 11 as illustrated in Figure 4 of the drawing, the curler member A assumes the position adjacent the scalp of the user. The operator proceeds to depress the finger portion 34 of the clamp 31 to release its grip upon the free end of the tress of hair and simul-

taneously depresses the catch 24 by pressing downwardly on the manipulating portion 30, thus releasing the tooth 27 from its keeper opening 28 and proceeds to pull outwardly upon the handle portion 22 to separate the winding key member B from its engagement with the curler member A. The curler member A remains upon the head of the user until such time as the curl has been formed. The curler member A is secured to the hair against accidental unwinding and separation by the clamping effect of the "bobby-like" pin clip 16. After the wound hair has set, the free end of the clip 16 is pulled outwardly to release its grip from the outer convolutions of the wound hair and the curler member A is withdrawn from the curl. By constructing the body of the curler member A in the form of a cage, the curler member is made lighter and also provides ventilating openings to hasten drying of the wound hair when water or lotion is used in the making of the curl.

Whereas the swivel head 15 is shown on what may be termed the outer end of the cage-like body 11, the same may be swivelly connected at the other end and provided with an opening for the insertion of the body portion 21 of the key member B.

In Figures 6 and 7 of the drawing I have illustrated a modified form of my invention in which the curler member is designated C and the winding key member D.

The curler member C comprises a cage-like body 40 having parallel rods 41, four of which have been shown and arranged in equi-distant axial relation with respect to an annular end collar 42 to which the outer ends of the rods are connected. The inner ends of the rods are bent inwardly and connected by solder or otherwise. Pivoted at 43 to the inner end of the body 40 is a clamping bar 44, the free end of the bar 44 being provided with a curled resilient locking head 45 for snapping engagement with the outer side of the collar 42 when in operative position as shown in dotted lines in Figure 6.

The winding key member D comprises a tubular body 46 and an integral handle 47. The body 46 is provided with four equi-distantly spaced slots 48 which extend inwardly from the outer free end thereof. The tubular body 46 is of a diameter to telescopically receive the cage-like body 40 with the four rods 41 respectively seated in the slots 48. The curler member C is inserted into the tubular body 46 with the bar 44 disengaged from the collar 42 and after insertion, the bar 44 is held against swinging by the jaws of a spring clip 49 which is fixedly attached to the handle 47. It is only after the hair has been wound upon the tubular body 46 and cage-like body 40 that the clamping bar 44 is released from the clip 49 and swung to a position to cause the same to clampingly engage the wound hair preparatory to the withdrawal of the winding key member D from the curler member C.

For releasably clamping the free end of the tress of hair to be waved, there is provided a clamp 50 pivoted to the handle 47 as at 51. The clamp 50 comprises a transversely curved jaw 52 which is complementary to the curvature of the tubular body 46 and which extends lengthwise thereof, and a depressible manipulating portion 53. A spring 54 presses against the manipulating portion 53 to urge the jaw 52 toward the tubular body 46.

To wind a tress of hair by the use of the device shown in Figures 6 and 7, the operator assembles

the curler member C and winding key member D as illustrated in Figure 6. The free end of the tress of hair is inserted between the jaw 52 and the tubular body 46 by first pressing down upon the manipulating portion 53 to effect an opening of the said jaw. The operator proceeds to turn the key member D to cause the tress of hair to be wound toward the scalp and upon the tubular body 46 and cage-like body 40. When the tress of hair is fully wound, the clamping bar 44 is released from the clip 49 and swung to the position shown in dotted lines in Figure 6, to cause the curler member C to be fixedly attached to the wound tress of hair. The operator may now press downwardly upon the manipulating portion 53 to release the clamping pressure upon the jaw 52 and proceeds to pull outwardly on the handle 47 until the tubular body 46 is free of the inner end of the cage-like body 40. The wound tress of hair is now held by the curler member C and remains thereon until such time as may be necessary to produce the desired curl.

The slots 43 separate the tubular body 46 into four tongs, the outer free ends are pointed to facilitate the insertion of the rods 41 of the cage-like body 40 into the slots to effect an interlocking of the members C and D so as to turn together during winding manipulation imparted to the key member D.

Having shown and described what I consider to be the most practical embodiments of my invention, I wish it to be understood that such changes in construction and design as come within the scope of the appended claims may be resorted to if desired.

Having thus described the invention, what I claim as new and desire to secure by Letters Patent of the United States, is:

1. A hair curling device comprising in combination, a tubular hair curler member, a spring clip carried by said curler member and extending substantially the length thereof and engaging therewith for gripping a tress of hair after it is wound thereon, a winding key member slidably insertable into and out of said tubular curler member, and releasable means for connecting the key member to the curler member when the key member is inserted therewith to facilitate the turning of the curler member upon manual turning of the winding key member to wind a tress of hair on the curler member and to facilitate the withdrawal and separation of the key member from the curler member when the tress of hair is fully wound thereon.

2. A hair curling device as set forth in claim 1 in which the releasable means includes a spring pressed depressible catch member carried by said winding key member, the catch member having a tooth, said curler member having a keeper opening to lockingly receive the tooth of said catch member.

3. A hair curling device comprising in combination, a tubular cage-like curler member open at one end, a key member including a body portion slidably extending into said curler member through the open end thereof, a manipulating portion extending axially from said body portion beyond the open end of said curler member, releasable interlocking means between said body portion and said curler member, and spring actuated clamp means carried by and extending lengthwise of said key member for clamping the free end of a tress of hair against the curler member for winding thereon by an operator imparting a manual turning movement to said ma-

nipulating portion, whereupon after complete winding of the tress of hair upon the curler member the operator may actuate the releasable interlocking means and withdraw the body portion from the curler member to leave the curler member upon the head of a user with the tress of hair wound thereon.

4. A hair curling device as set forth in claim 3, in which the clamping means includes a spring pressed clamping member pivoted to the manipulating portion of said key member having a clamping jaw overlying the exterior of the curler member and substantially parallel thereto to hold the free end of the tress of hair during the winding operation.

5. A hair curling device comprising in combination, a cylindrical curler member having a tubular cage-like body open at one end, a head swivelly connected to the other end of said curler member, a resilient clamp having an elongated body portion normally extending substantially parallel to said tubular body and an inwardly extending loop portion at one end which is fixedly connected to said head whereby the convolutions of a tress of hair wound upon the curler member may be gripped between the resilient clamp and the tubular body, and a key member fitting into said tubular body and having a manipulating portion extending outwardly therebeyond, releasable means fixedly securing the key member to said tubular body, and a spring pressed clamp carried by said key member and cooperating with the body of said curler member to secure the free end of a tress of hair therebetween.

6. A hair curling device comprising in combination, a tubular curler member open at one end, a head swivelly mounted in the other end of said curler member, a clamping element extending the length of said curler member exteriorly thereof and normally engaging the same and having a resilient loop portion at one end fixedly connected to said head, a key member having a body portion fitting within the curler member through the open end thereof, a manipulating portion connected to said body portion and extending beyond the open end of said curler member, releasable interlocking means between the body portion and the curler member for turnably connecting the same together, a clamp member pivoted to said manipulating portion and having an elongated jaw extending substantially parallel to said curler member and between which the free end of a tress of hair to be wound is adapted to be held, and spring means acting to forcibly urge the jaw toward the curler member.

7. A hair curling device comprising in combination a cylindrical curler member, a manipulating element, means releasably connecting the manipulating element to the curler member, clamp means carried by the manipulating element for clamping the free end of a tress of hair to be wound against the curler member, and resilient clamp means swivelly connected to said curler member for gripping the convolutions of a wound tress of hair when wound upon said curler member, whereby the releasable means may be actuated after winding of a tress of hair upon the curler member to facilitate the separation of the manipulating element from the curler member while the wound tress of hair is undisturbed and remains upon the curler member.

8. A hair curling device comprising in combination, a tubular cage-like curler member having spaced radially arranged longitudinal bars,

a winding key member including a tubular body portion and a handle portion, radially arranged slots provided in the tubular body extending inwardly from the outer free end thereof and corresponding in number to the number of longitudinal bars, the slotted portion of the tubular body telescoping said cage-like body with the longitudinal bars thereof being respectively disposed in said slots, a spring actuated clamp carried by said handle for clamping the free end of a tress of hair against said tubular body, and a clamp carried by said cage-like body for clamping the cage-like curler member to a wound tress of hair when wound thereon by turning manipulation imparted to said winding key member.

9. A hair curling device as set forth in claim 8 in which the clamp carried by the cage-like member is pivoted to the inner end thereof, means carried by the handle of the winding key member for holding the clamp in an inoperative out of the way position, and a resilient head provided on the free end of the clamp and frictionally engageable with the outer end of the cage-like body for securing the clamp in operative clamping position relative to said cage-like body.

MAX HABERMAN.
